(57) **CLAIM**

The ornamental design for a makeup tool organizer, as shown and described.

DESCRIPTION

FIG. 1 is a perspective view of a makeup tool organizer, showing my new design.

FIG. 2 is a front view of FIG. 1.

FIG. 3 is a rear view of FIG. 1.

FIG. 4 is a left side view of FIG. 1. The right side view of FIG. 1 is a mirror image of the left side view of FIG. 1.

FIG. 5 is a top plan view of FIG. 1; and,
FIG. 6 is a bottom plan view of FIG. 1.

The broken lines are shown for illustrating portions of the article, and form no part of the claimed design.

1 Claim, 6 Drawing Sheets
